[57] CLAIM

The ornamental design for a feminine urinary conduit,
as shown and described.

DESCRIPTION

FIG. 1 is a top plan view of a feminine urinary conduit,
showing our new design;

FIG. 2 is a left side elevational view thereof;

FIG. 3 is a right side elevational view thereof;

FIG. 4 is a bottom plan view thereof;

FIG. 5 is a perspective view thereof; and

FIG. 6 is a left side perspective view thereof.
